UNITED STATES PATENT OFFICE.

HARRY S. McCORMACK, OF NEW YORK, N. Y., ASSIGNOR TO UNDERWOOD
TYPEWRITER COMPANY, OF NEW YORK, N. Y., A CORPORATION OF NEW
JERSEY.

TYPE-WRITING MACHINE.

No. 848,764.

Specification of Letters Patent.

Patented April 2, 1907.

Application filed January 17, 1907. Serial No. 352,711.

To all whom it may concern:

Be it known that I, HARRY S. McCORMACK, a citizen of the United States, residing in New York, in the county of New York and State 5 of New York, have invented certain new and useful Improvements in Type-Writing Machines, of which the following is a specification.

This invention relates to type-writing machines in which, in addition to the usual line-spacing mechanism for the revoluble platen, there is provided an auxiliary mechanism, usually at one end of the platen, for feeding a paper ribbon around the platen independently of the latter or while the platen is stationary. Such strips are employed for the purpose of recording the amounts of successive bills as the latter are written upon the main portion of the platen. During the 15 writing of the bill the tally-strip remains stationary, and when the bill is completed the operator copies the amount thereof onto the tally-strip, so that the latter at the end of the day may show the total amount of 20 business transacted.

The principal objects of one portion of my invention are to provide improved means for holding the paper ribbon or tally-strip and to mount the same in such a manner that they 25 will be out of the way of the operator, so as not to interfere or obstruct the placing of wide sheets in the machine or the manipulation of such wide sheets.

The ribbon I carry upon two spools. The 30 delivery-spool I place behind the paper-shelf, which is usually provided in rear of the platen. In this position said delivery-spool cannot possibly interfere with the operator in inserting or manipulating the wide sheets. 35 The receiving-spool I place close to the platen and sufficiently forward of the paper-shelf to be well out of the way of the operator's hands while he is handling the wide or main sheets. I carry the paper ribbon between said spools over a platen, which I 40 preferably make of far smaller cross-section than the main platen, thereby giving clearance for said receiving-spool, the flanges of the latter overlapping the end of the main platen. 45 Hence a very compact, simple, and inexpensive paper-ribbon mechanism is secured, and the operator is not bothered thereby

when inserting, adjusting, or withdrawing the usual wide sheets.

In the preferred form of the invention the auxiliary platen is stationary—that is, it is fixed to the platen-frame at the end of the main platen and does not move during the line-feeding of the paper ribbon. The latter may be fed in any desired manner; but I 55 prefer to wind it by means of a ratchet-wheel connected to the receiving-spool and to operate the ratchet-wheel by a pawl which is attached to the mechanism which is usually provided for releasing the rolls which press 60 the wide sheets against the main platen to feed the sheets therearound. Provision is made for adjusting the auxiliary platen relatively to the types, so that its printing-surface may be brought into exact alinement or 65 flush with the printing-line on the platen, and hence perfect type impressions obtained on the paper ribbon. Said delivery-spool is preferably mounted on a hinged frame, so that at the end of the day it may be swung 70 forwardly of the paper-shelf, so as not to be in the way of the cover which is usually placed upon the machine.

Another feature of the invention relates to means for securing accurate sidewise gaging 75 of the main sheets. I provide a scale extending along said paper-shelf and attach to the paper-shelf a pair of side guides for the sheets, with means to clamp the guides. Each of the latter is provided with an index 80 to coöperate with said scale to set the guides thereby.

Other features and advantages will herein-after appear.

In the accompanying drawings, Figure 1 is 85 a front perspective view of the platen-frame of an "Underwood" type-writing machine provided with my improvements. Fig. 2 is a sectional end elevation of the paper-ribbon devices, the delivery-spool being shown by 90 full lines in working position and by dotted lines in a position of disuse. Fig. 3 illustrates the manner of line-feeding the paper strip by means of a pawl connected to the usual pressure-roll-releasing means. Fig. 4 is a sectional view showing the relation of the 95 parts at Fig. 2. Fig. 5 is a sectional plan of the rear part of the paper-shelf, showing the manner of releasably hinging the delivery- 100

spool thereon. Fig. 6 illustrates the manner of releasably connecting the delivery-spool to its axle. Fig. 7 is a perspective view of a gage for the side edges of the sheets, and Fig. 8 is a sectional view illustrating the same as applied to a paper-shelf. Fig. 9 illustrates a part of the sheet-gaging means.

A cylindrical platen 1 is revolvably mounted, by means of an axle 2, in the ends 3 of a platen-frame, which usually carries or comprises a paper-shelf 4, inclining upwardly and rearwardly from the rear side of the platen to aid in the introduction of sheets into the machine. In said Underwood machine types 5 are mounted on bars 6 to strike rearwardly against the front side of the platen. The platen is rotated by a ratchet-wheel 7 and a reciprocating pawl 8. Front and rear pressure-rolls 9 10 serve to press the sheets against the platen, the pressure being applied by means of springs 11. A rock-shaft 12 has means to release said rolls, said means being well known and requiring no description. The rock-shaft is connected by a link 13 to a lever 14, pivoted at 15 upon an end of the platen-frame and provided with a finger-piece 16, so that upon depressing said finger-piece the pressure-rolls 9 10 are withdrawn from the platen to permit the ready insertion or withdrawal of sheets of paper. The lower portion of the paper-shelf 4 curves forwardly and upwardly around the platen at 17 to guide the paper. The parts so far described are in common use on said Underwood type-writing machine.

At the right-hand end of the main platen 1 I mount an auxiliary platen 18, which is fixed to the platen-frame in position to be written upon by the types 5. Over this auxiliary platen is carried a paper ribbon or tally-strip 19 from a delivery-spool 20 to a receiving-spool 21. The receiving-spool 21 is supported upon a fixed rod 22, which in said machine usually extends from one end of the platen-frame to the other and carries front paper-guiding fingers. (Not shown.)

The auxiliary platen 18 may be in the form of a segment of a cylinder, as illustrated, and its surface may consist of rubber similar to the usual surface of the platen 1, and in the form of the invention illustrated said segment consists of a portion carved out from such a cylinder, as 1, the rubber facing being backed up by a segment 23 of the wooden core upon which the rubber facing of the platen 1 is usually secured.

The auxiliary platen is mounted between a pair of plates 24 25, which are loosely mounted upon the platen-axle 2. Also mounted upon said axle is a pair of arms 26 27, confined between said plates and extending backwardly and upwardly to the rod 22 to be held thereby against rotation about the axle 2. The surface of the auxiliary platen

18 is curved a little eccentrically to the platen-axle 2 and adjustable about said axle to rotate different portions of said segment into the printing field to adjust the segment to the types. It will be seen that the printing-surface of 18 is capable of considerable up and down adjustment while remaining within the printing field, and hence there may be presented to the types that portion of said surface which is exactly flush with the surface of the main platen 1. This provision of adjusting the auxiliary platen relatively to the types is of importance in machines like the Underwood, where the type-bars are caused to strike against an anvil 28, whereby they are arrested and the types are caused to spring backward to strike the platen. The plate 25, Fig. 2, has a curved slot 29, and a screw 30, passing through said slot, is threaded into the arm 26 to secure the segmental platen 18 where it is adjusted.

The plates 24 25 are rigidly connected by posts 31, 32, and 33, and a paper-guiding shield 34 extends across from one plate to the other beneath the segment to guide the paper ribbon 19 forwardly and upwardly to said segment, said shield forming approximately a continuation of the segment and curving from the lower edge thereof rearwardly and upwardly, as seen at Fig. 4. The roll 35 may be provided upon the post 33 to guide the paper ribbon from the auxiliary platen or segment back to the spool 21.

The arms 26 27, which are rigidly connected at their lower ends by bolts or rivets 36, are perforated at their upper ends to fit upon a hollow shaft 37, which forms the axle upon which the spool 21 turns, said shaft fitting loosely upon the rod 22. The spool 21 has a metal bushing 38, which is attached to said hollow shaft by a set-screw 39. The spool-flanges 40 are secured upon the spool 21 in any suitable manner and overlap the end of the platen 1, as seen at Fig. 4, the auxiliary platen 18 being sufficiently small in cross-section to give the required clearance to the flanges 40 or to the paper wound upon the spool 21. The latter is confined between the arms 26 27.

Upon the outer end of the shaft 37 is fixed a ratchet-wheel 41, operated by a pawl 42, pivoted at 43 upon the upper end of the link 13, which forms part of the mechanism that releases pressure-rolls 9 10, Fig. 3, so that whenever the pressure-rolls are released to permit a main sheet to be withdrawn and a fresh one inserted the ratchet-wheel 41 is rotated by the pawl and the paper ribbon 19 given a line-feeding movement accordingly. Thus the line-feeding is effected without attention on the part of the operator, and the liability of his failing to feed the strip between entries thereon is avoided. Said spool 21 draws the paper forwardly from the spool 20 and over a tubular part 44, formed along

the upper edge of the paper-shelf 4, and thence down to the shield 34 and forwardly around the same and up to the auxiliary platen 18 and thence backwardly to wind upon the spool 21. To prevent overthrow of the latter, a brake 45 is suitably secured upon the roll 22. The spool 20 is in the form of a sleeve or core slipped upon an axle or holder 46, which is secured by a screw 47 to the rear end of an arm 48, which extends backwardly and downwardly from the top of the paper-shelf 4. The axle 46 may carry a flange 49, and the spool 20 may carry a co-operating flange 50 to confine the roll 51 of paper ribbon. Upon the hub 52, secured to the flange 50, may be provided a yielding spring-finger 53, fitted in a slot 54 in the hub and projecting down into a groove 55, formed in the end of the axle 46, thereby releasably holding the spool 20 upon the axle.

The arm 48 is attached to the outer end of a pintle 56, whereby the arm is hinged upon the platen-frame to turn from the full-line to the dotted-line position at Fig. 2, thereby 25 swinging the delivery-spool 20 from a position of use back of the paper-shelf to a position of disuse forward of the same. Said pintle is revolvably supported in a bushing 57, secured within the tubular part of rim 44 of the paper-shelf. At its outer projecting end said bushing 57 is diagrammatically recessed at 58 to receive the arm 48 and lock the same against rotation. A compression-spring 59, surrounding the inner end of the pintle, bears at 35 one end against the bushing 57 and at the other end against a cap 60, provided upon said pintle to hold the arm 48 yieldingly within said recess. In order to turn the arm, it is pulled out from the full-line to the 40 dotted-line position at Fig. 5, and upon being swung to the dotted-line position at Fig. 2 the spring 59 draws the arm again into said recess.

Along the paper-shelf 4 extend two long slots 61 62, through which project rearwardly lugs 63, riveted at 64 upon the backs of a pair of paper-guiding plates 65, which lie upon the front side of the paper-shelf. The outer edges of said plates are bent up at 66 67 to form opposite gages for the side edges of the wide sheets of paper introduced into the machine. These gages may be adjusted along the platen or along the paper-shelf to points determined by a scale 68, the tops of 55 the gages 66 being extended at 69 to form indexes to co-operate with said scale. The guides may be secured by means of eccentric cams 70, secured by pivot-screws 71 upon the lug 13, and having handles 72, whereby they 60 may be turned to draw back the plates 65 firmly against the front of the paper-shelf and cramp the same thereto, as at Fig. 8.

Variations may be resorted to within the scope of the invention and portions of the improvements may be used without others.

Having thus described my invention, I claim—

1. In a type-writing machine, the combination with a revoluble main platen and a platen-frame, of an auxiliary platen fixed rigidly to the platen-frame at the end of the main platen.

2. In a type-writing machine having a revoluble main platen, a platen-frame and means for feeding paper around the platen, 75 the combination of an auxiliary platen fixed rigidly to the platen-frame at the end of the main platen and flush therewith, and means for drawing a paper ribbon around the auxiliary fixed platen.

3. In a type-writing machine having types, a revoluble main platen and a platen-frame, the combination with an auxiliary platen fixed rigidly to the platen-frame at the end of the main platen, of means for adjusting the 85 auxiliary platen toward and away from the types.

4. In a type-writing machine having types, a revoluble main platen and a platen-frame, the combination with an auxiliary platen in 90 the form of a segment of a cylinder at the end of the main platen, said segment being provided with an eccentric hinge whereby it is supported upon the platen-frame, of means for securing the segment rigidly to the platen-frame in different positions to which the segment is adjusted about said hinge.

5. In a type-writing machine having a revoluble main platen, a platen-frame and means for feeding paper around the platen, 100 the combination of an auxiliary platen fixed rigidly to the platen-frame at the end of the main platen and flush therewith, means in rear of the auxiliary platen for holding a paper-ribbon spool, a second spool for drawing the ribbon off from the auxiliary platen, and line-spacing mechanism for the second spool.

6. In a type-writing machine having a revoluble main platen, a platen-frame, means 110 for feeding paper around the platen and a line-spacing mechanism, the combination of an auxiliary platen fixed rigidly to the platen-frame at the end of the main platen and substantially coincident therewith, a spool in 115 line with said auxiliary platen to receive a paper ribbon, and line-spacing mechanism to turn said spool to draw the ribbon over the auxiliary platen.

7. In a type-writing machine, the combination with a revoluble main platen and a platen-frame, of an auxiliary platen fixed rigidly to the platen-frame at the end of the main platen, and mechanism independent of the main platen for effecting intermittent 125 line-feeding movements of a paper ribbon over said auxiliary platen.

8. In a type-writing machine, the combination with a revoluble main platen and a platen-frame, of an auxiliary platen fixed 130

rigidly to the platen-frame at the end of the main platen, a delivery-spool and a receiving-spool in line with said auxiliary platen, and line-spacing mechanism connected to the receiving-spool to draw a paper ribbon from said delivery-spool over said auxiliary platen.

9. In a type-writing machine, the combination with a revoluble main platen and a platen-frame, of an auxiliary platen fixed rigidly to the platen-frame at the end of the main platen, a delivery-spool holder, a curved plate forming approximately a continuation of the fixed platen and extending back therefrom toward said spool-holder to form a surface around which the paper ribbon may run to the fixed platen, and means for drawing the paper ribbon from the fixed platen.

10. In a type-writing machine, the combination with a revoluble main platen and a platen-frame, of an auxiliary platen fixed rigidly to the platen-frame at the end of the main platen, a delivery-spool and a receiving-spool in line with said auxiliary platen, line-spacing mechanism connected to the receiving-spool to draw a paper ribbon from said delivery-spool over said auxiliary platen, and guiding devices over which the paper ribbon may run between the delivery-spool and the fixed platen and between the latter and the receiving-spool.

11. In a type-writing machine having a revoluble main platen, a platen-frame and a paper-shelf, the combination of an auxiliary platen at one end of the main platen, a receiving-spool in juxtaposition to the auxiliary platen, the latter being of reduced cross-section as compared to said main platen, to give clearance to said receiving-spool, the platens being flush at the printing-line, and a delivery-spool mounted upon the platen-frame in rear of the paper-shelf.

12. In a type-writing machine having a revoluble main platen and a platen-frame, the combination of an auxiliary platen between the main platen and one end of the platen-frame, and means to feed a paper ribbon around said auxiliary platen, said feeding means including a spool around which the paper ribbon is wound, said spool having flanges overlapping the end of the main platen, and the auxiliary platen being of reduced cross-section as compared to said main platen, to give clearance for said flanges, the platens being flush at the printing-line.

13. In a type-writing machine having a revoluble platen and a pressure-roll to run upon the platen and mechanism for releasing the pressure-roll, the combination of a spool for winding a paper ribbon independently of said platen, a ratchet-wheel for said spool, and a pawl connected to said releasing mechanism for operating said ratchet-wheel.

14. In a type-writing machine provided with types, the combination of means for

supporting a main sheet and a paper ribbon side by side in position to be written upon by the types, said means including a revoluble platen and a roll for pressing the main sheet against the revoluble platen, means for releasing said roll, and means controlled by said releasing means for feeding the paper ribbon line by line.

15. In a type-writing machine having a revoluble platen, a pressure-roll to run thereon, and means to release the pressure-roll, the combination with an auxiliary platen at the end of the main platen, of means controlled by said releasing means for feeding a paper ribbon, line by line over said auxiliary platen.

16. In a type-writing machine having a revoluble platen, a pressure-roll to run thereon, and means to release the pressure-roll, the combination with an auxiliary platen at the end of the main platen, of means controlled by said releasing means for feeding a paper ribbon line by line over said auxiliary platen, said feeding means including a pawl connected to said releasing means, and a ratchet-wheel rotated by said pawl and connected to a rotary device for feeding the paper ribbon.

17. In a type-writing machine having a revoluble platen, a pressure-roll to run thereon, and means to release the pressure-roll, the combination with an auxiliary platen at the end of the main platen, of a spool for drawing a paper ribbon from said auxiliary platen, a ratchet-wheel for said spool, and a pawl operated by said releasing means to turn said ratchet-wheel.

18. In a type-writing machine having a revoluble main platen, a platen-frame and a paper-shelf in rear of the platen, the combination of an auxiliary platen at one end of the main platen, a receiving-spool in juxtaposition to the auxiliary platen, the latter being of reduced cross-section as compared to said main platen, to give clearance to said receiving-spool, and a delivery-spool holder mounted on the platen-frame to move from a position of use back of the paper-shelf to a position of disuse forward of the paper-shelf.

19. In a type-writing machine having a revoluble platen, a platen-frame and a paper-shelf in rear of the platen, and also having means to coöperate with the platen to feed wide sheets around the same, the combination of a receiving-spool forward of the paper-shelf, a delivery-spool coöoperating therewith to feed a paper ribbon alongside of the wide sheets, and a line-feeding device for the receiving-spool; said delivery-spool mounted to move from a position of use back of the paper-shelf to a position of disuse forward of the paper-shelf.

20. In a type-writing machine having a revoluble platen, a platen-frame and a paper-shelf in rear of the platen, the combination of

an arm carrying at one end a spool-holder and hinged at the other end upon the platen-frame, so that the spool-holder may be swung from the rear side to the front side of the platen, and yielding means for mechanically locking said arm in either such position.

21. In a type-writing machine having a revoluble platen and a paper-shelf in rear of the platen, the upper end of the paper-shelf being curved in tubular form, a bushing within the tubular portion of the paper-shelf, a pintle extending through the bushing, an arm fixed upon the pintle and carrying a holder for a paper-spool, said bushing recessed at its outer end to receive said arm and lock the same against rotation, and a spring connected to said pintle to draw said arm into the recess.

22. In a type-writing machine having a revoluble main platen provided with an axle, a platen-frame, a paper-shelf in rear of the platen, and a rod mounted upon the platen-frame and extending along the platen in rear thereof, the combination of an auxiliary platen in the form of a segment at one end of the main platen, plates upon which said auxiliary platen is mounted, said plates mounted upon said platen-axle, and a pair of arms mounted upon said axle and confined between said plates and extending back to said rod to be held in position thereby, said platen-segment being curved eccentrically to said platen-axle and adjustable about said axle to rotate different portions of the segment into the printing-field to adjust the segment to the types.

23. In a type-writing machine having a revoluble main platen provided with an axle, a platen-frame, a paper-shelf in rear of the platen, and a rod mounted upon the platen-frame and extending along the platen in rear thereof, the combination of an auxiliary platen in the form of a segment at one end of the main platen, plates upon which said auxiliary platen is mounted, said plates mounted upon said platen-axle, and a pair of arms mounted upon said axle and confined between said plates and extending back to said rod to be held in position thereby, said platen-segment being curved eccentrically to said platen-axle and adjustable about said axle to rotate different portions of the segment into the printing-field to adjust the segment to the types, one of said plates having a closed slot to receive a screw which is threaded into one of said arms to secure the segment where adjusted, a hollow shaft mounted upon said rod, a receiving-spool fixed upon said shaft, a ratchet-wheel also fixed upon said shaft, a pawl connected to said pressure-roll-releasing mechanism to operate said ratchet-wheel, a paper-guiding shield below said segment and forming approximately a continuation thereof and curving from the lower edge of said segment rearwardly and upwardly, and a delivery-spool from which the paper ribbon is led forwardly beneath and around said shield and up in front of said segment and back to said receiving-spool.

24. In a type-writing machine having a revoluble main platen provided with an axle, a platen-frame, a paper-shelf in rear of the platen, a pressure-roll running upon the

platen, a mechanism for releasing said pressure-roll, and a rod mounted upon the platen-frame and extending along the platen in rear thereof, the combination of an auxiliary platen in the form of a segment at one end of the main platen, plates upon which said auxiliary platen is mounted, said plates mounted upon said platen-axle, a pair of arms mounted upon said axle and confined between said plates and extending back to said rod to be held in position thereby, said platen-segment being curved eccentrically to said platen-axle and adjustable about said axle to rotate different portions of the segment into the printing-field to adjust the segment to the types, one of said plates having a slot to receive a screw which is threaded into one of said arms to secure the segment where adjusted, a hollow shaft mounted upon said rod, a receiving-spool fixed upon said shaft, a ratchet-wheel also fixed upon said shaft, and a pawl connected to said pressure-roll-releasing mechanism to operate said ratchet-wheel.

25. In a type-writing machine having a revoluble main platen provided with an axle, a platen-frame, a paper-shelf in rear of the platen, a pressure-roll running upon the platen, a mechanism for releasing said pressure-roll, and a rod mounted upon the platen-frame and extending along the platen in rear thereof, the combination of an auxiliary platen in the form of a segment at one end of the main platen, plates upon which said auxiliary platen is mounted, said plates mounted upon said platen-axle, a pair of arms mounted upon said axle and confined between said plates and extending back to said rod to be held in position thereby, said platen-segment being curved eccentrically to said platen-axle and adjustable about said axle to rotate different portions of the segment into the printing-field to adjust the segment to the types, one of said plates having a slot to receive a screw which is threaded into one of said arms to secure the segment where adjusted, a hollow shaft mounted upon said rod, a receiving-spool fixed upon said shaft, a ratchet-wheel also fixed upon said shaft, a pawl connected to said pressure-roll-releasing mechanism to operate said ratchet-wheel, a paper-guiding shield below said segment and forming approximately a continuation thereof and curving from the lower edge of said segment rearwardly and upwardly, and a delivery-spool from which the paper ribbon is led forwardly beneath and around said shield and up in front of said segment and back to said receiving-spool.

26. In a type-writing machine having a revoluble main platen provided with an axle, a platen-frame, a paper-shelf in rear of the platen, a pressure-roll running upon the platen, a mechanism for releasing said pressure-roll, and a rod mounted upon the platen-frame and extending along the platen in rear

thereof, the combination of an auxiliary platen in the form of a segment at one end of the main platen, plates upon which said auxiliary platen is mounted, said plates mounted upon said platen-axle, a pair of arms mounted upon said axle and confined between said plates and extending back to said rod to be held in position thereby, said platen-segment being curved eccentrically to said platen-axle and adjustable about said axle to rotate different portions of the segment into the printing-field to adjust the segment to the types, one of said plates having a slot to receive a screw which is threaded into one of said arms to secure the segment where adjusted, a hollow shaft mounted upon said rod, a receiving-spool fixed upon said shaft, a ratchet-wheel also fixed upon said shaft, a pawl connected to said pressure-roll-releasing mechanism to operate said ratchet-wheel, a paper-guiding shield below said segment and forming approximately a continuation thereof and curving from the lower edge of said segment rearwardly and upwardly, a delivery-spool from which the paper ribbon is led forwardly beneath and around said shield and up in front of said segment and back to said receiving-spool, an arm having a stud whereon said delivery-spool is mounted, a pintle whereon said arm is secured, a bearing upon said paper-shelf wherein said pintle may turn and also move axially, said bearing being provided at its end with a diametrical recess in which said arm fits so that the arm is locked against rotation, and a spring upon said pintle for holding said arm in said recess, said arm being reversible in the recess, so as to move the spool from a position of use in rear of the bearing to a position of disuse in front of the bearing.

27. In a type-writing machine having a revoluble main platen provided with an axle, a platen-frame, a paper-shelf in rear of the platen, the combination of an auxiliary platen in the form of a segment at one end of the main platen, a receiving-spool, a delivery-spool from which the paper ribbon is led forwardly beneath and up in front of said segment and back to said receiving-spool, an arm having a stud whereon said delivery-spool is mounted, a pintle whereon said arm is secured, and a bearing whereon said pintle may turn.

28. In a type-writing machine having a platen and a paper-shelf in rear of the platen, the combination of a scale provided upon the front of said paper-shelf, a paper-guide in front of said paper-shelf and having a gage

for the side edge of the sheets, said gage provided with an index to coöperate with said scale, and means to clamp the paper-guide.

29. In a type-writing machine having a platen and a paper-shelf in rear of the platen, the combination of a scale provided upon the front of said paper-shelf, the latter being slotted along said scale, a paper-guide in front of said paper-shelf and having a gage for the side edge of the sheets, said gage provided with an index to coöperate with said scale, a tongue provided upon said paper-guide and projecting rearwardly through the slot in the paper-shelf, and a cam provided with a handle and pivoted upon said tongue to bind against the rear side of the paper-shelf to clamp the paper-guide thereto.

30. In a type-writing machine having a platen and a paper-shelf in rear of the platen, the combination of a scale provided upon the front of said paper-shelf, a pair of paper-guides in front of said paper-shelf and having opposite gages for the side edges of the sheets, said gages provided with indexes to coöperate with said scale, and means to clamp the paper-guides to the paper-shelf.

31. In a type-writing machine having a platen and a paper-shelf in rear of the platen, the combination of a scale provided upon the front of said paper-shelf, the latter being slotted along said scale, a pair of paper-guides in front of said paper-shelf and having opposite gages for the side edges of the sheets, said gages provided with indexes to coöperate with said scale, tongues provided upon said paper-guide and projecting rearwardly through the slots in the paper-shelf, and cams provided with handles and pivoted upon said tongues to bind against the rear side of the paper-shelf to clamp the paper-guides thereto.

32. In a type-writing machine having a revoluble platen and a paper-shelf inclining upwardly and rearwardly from the rear side of the platen, so as to leave a substantial space between the platen and the paper-shelf, the combination with a paper-carrying spool, of means whereon said spool is mounted to move from a position in rear of the paper-shelf to a position within said space between said platen and said paper-shelf; said spool having provision for mechanically determining each of said positions thereof.

HARRY S. McCORMACK.
